UNITED STATES PATENT OFFICE.

GEORGE E. BAUMBERGER AND JOHN DISTELHORST, OF BURLINGTON, IOWA.

VEHICLE-BRAKE.

SPECIFICATION forming part of Letters Patent No. 769,047, dated August 30, 1904.

Application filed February 4, 1904. Serial No. 191,991. (No model.).

To all whom it may concern:

Be it known that we, GEORGE E. BAUMBERGER and JOHN DISTELHORST, citizens of the United States, and residents of Burlington, in the county of Des Moines and State of Iowa, have made a certain new and useful Invention in Vehicle-Brakes; and we declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a perspective view of the invention as applied. Fig. 2 is a detail side view of the lever *b* broken away at the top.

The invention has relation to means for operating the brakes of vehicles; and it consists in the novel construction and combinations of parts, as hereinafter set forth.

In the accompanying drawings, illustrating the invention, the letter *a* designates the side of a wagon body or frame, and *b* the brake-lever; *c*, the upper rack; *d*, the lower rack, and *e* the connection-rod to the brake. The upper rack *c* has its teeth *g* projecting horizontally outward, and it is provided with a loop-guard *h*, extending alongside the rack, but at a sufficient distance therefrom to permit the brake-lever to be easily operated in regard to its engagement with or disengagement from this rack. The lower rack *d* is located parallel to the upper rack and at a sufficient distance therefrom to provide for leverage. This is a fulcrum-rack, and its line of teeth or projections *p* between the fulcrum-bearings *k* extends horizontally, while the teeth or projections are vertical.

The brake-lever *b* has at its lower end portion a loop *v*, which engages the rack-bar of the lower rack, which is set out from the frame-body in such wise that the loop of the lever extends around the same, embracing it loosely.

The loop *v* is long enough to allow the lever sufficient motion of reciprocation to permit the disengagement of the fulcrum-pins, which

is located in the loop near its upper end, from any one of the fulcrum-bearings *k*. The lever is also provided with an elongated catch *t*, which extends along its rear edge and is inclined inward or toward the teeth of the upper rack, with which it is designed to engage. This catch *t* is a little longer than the loop *v*, being so arranged that it can be brought into engagement with the upper rack in any position of the lever. This elongated catch can be readily formed by twisting the metal bar in making the lever. It is apparent that when there is any tension on the brake connection *e* the catch will be held in engagement with the upper rack. The fulcrum-pivot of the lever being adjustable, its position with relation to the upper rack can be changed when desired, so as to make it more convenient in operation for the driver or for such other purpose as may render it advisable. The lever by reason of its gravity holds its position in engagement with one of the fulcrum-bearings of the lower rack, and when it is desired to change the bearing the lever is lifted, and the upper rack then running as a fulcrum for making the change is readily moved to position above the fulcrum-bearing desired and dropped, its fulcrum-pin engaging the bearing.

Having described this invention, what we claim, and desire to secure by Letters Patent, is—

The combination with a brake-rack having a guard-loop, of a fulcrum-rack parallel thereto, and a vertically-adjustable brake-lever having a terminal loop embracing said fulcrum-rack and forming a stop to limit upward movement of the lever, and a fulcrum-pin at the upper end of said loop and connecting loop and lever, substantially as specified.

In testimony whereof we affix our signatures in presence of two witnesses.

GEORGE E. BAUMBERGER.
JOHN DISTELHORST.
